PHONOGRAPH

Heinrich F. Max Gramann, Orange, N. J., assignor to Thomas A. Edison, Incorporated, West Orange, N. J., a corporation of New Jersey

Application June 16, 1933, Serial No. 676,037

2 Claims. (Cl. 274—21)

This invention relates to phonographs and more particularly to phonographs of the business or commercial type, which are adapted to record as well as to reproduce dictation. This invention is especially directed to a novel and improved construction for back-spacing the arm or carriage which carries the recording and reproducing mechanism so as to cause repetition of any portion of the record whenever the operator of the machine so desires.

Phonographs designed for both recording and reproducing dictation are now generally so constructed and arranged that the carriage for the recording and reproducing mechanism may at any time be manually moved or spaced back with respect to the record tablet, so as to reproduce previously recorded matter on said tablet. When a dictator, using such a phonograph for recording dictation, desires to reproduce previously dictated matter, it is necessary—first, to manually readjust the recording and reproducing mechanism to neutral position; second, to move the carriage backwardly along the record tablet a distance depending upon the amount of matter to be reproduced; and third, to set the recording and reproducing mechanism in reproducing position. The apparatus is then in condition for reproducing and the dictator may listen to the recorded matter. When the reproduction of such matter has been completed and it is desired to dictate further, it is necessary for the dictator to again manipulate the recording and reproducing mechanism to return it to the recording position. Such manipulations incident to a repeating operation in the normal use of dictating machines are distracting in addition to requiring considerable of the dictator's time. Dictators may often neglect to recondition the recording and reproducing mechanism for recording after completing reproduction and in consequence they proceed to dictate while the reproducing stylus remains in engagement with the record tablet with the result that no recording is obtained. Warning signals have been provided to warn the dictator under these circumstances, but such signals are frequently ineffective because of the concentration of the dictator on the subject of the dictation.

The primary object of this invention is to provide a novel and effective back-spacing construction or mechanism, easily adaptable to the above described type of phonograph or dictating machine, and by which the back-spacing of the recorder-reproducer may be easily and quickly effected without distractive manipulation on the part of the dictator.

Another object of the invention is to provide in a recording and reproducing phonograph, an improved mechanism for back-spacing which will simultaneously disengage the recording stylus from the record tablet and bring the reproducing stylus into engagement with said record tablet.

A further object of the present invention is to provide a novel means for automatically re-conditioning the machine for recording after the reproduction of the matter recorded within the back-spaced area has been effected.

A still further object of this invention is to provide a mechanism for the purposes stated above, which can be controlled from a point remote from the phonograph proper.

Further objects and features of my invention will be disclosed in the following specification and appended claims.

For a clearer understanding of my invention, attention is directed to the drawings, accompanying and forming part of this specification, wherein:

Figure 1 is a front elevation of a phonograph having a preferred embodiment of my invention applied thereto;

Fig. 2 is a top plan view partly broken away, of the phonograph of Fig. 1;

Fig. 3 is an enlarged side elevational view, partly in section of the carriage and associated parts of the phonograph of Fig. 1, the recording and reproducing mechanism being positioned for recording;

Fig. 3A is a further enlarged plan view, partly in section, of the mechanism at the rear right corner of the carriage as seen from above;

Fig. 4 is a view of the mechanism of Fig. 3 as seen from below;

Fig. 5 is a fragmental view of the mechanism carried by the carriage in the position occupied immediately after a back-spacing movement has been effected;

Fig. 6 is a sectional view taken substantially on the line 6—6 of Fig. 5;

Fig. 7 is a rear elevational view, partly in section, of the carriage shown in Fig. 3;

Fig. 8 is a fragmental view of the rear portion of the carriage taken from the left-hand side as seen in Fig. 1;

Fig. 9 is a cross sectional view showing in detail the feed wheel of the phonograph of Fig. 1 and its support;

Fig. 10 is an elevational view, partly in section, showing the mouthpiece of the dictating machine including the means for remotely controlling the operation of my improved back-spacing mecha-

nism; the electrical circuit employed to control said mechanism being shown schematically;

Fig. 11 is a plan view of the mouthpiece of Fig. 10 as seen from above;

Fig. 12 is a section taken on line 12—12 of Fig. 11; and

Fig. 13 is an elevation, partly in section and with parts omitted, of the rear portion of the carriage and associated mechanism.

10 The phonograph is of well known construction and comprises a base 4 having upright standards 3, 7 and 7'. A mandrel 1 for supporting a record tablet A is carried by a shaft 2 journaled in the standard 3. The mandrel shaft 2 is connected 15 through a suitable clutch 9, 10 to a drive pulley 5 which in turn is connected by a belt 8 to a driving motor (not shown). A feed screw 20, driven from the mandrel shaft by gears 22, 23 is provided for moving a carriage 13 transversely of the record tablet A. A pair of guide rods 17, 18 supported by the standards 7, 7' are provided for slidably supporting the carriage 13. Guide rods 17 and 18 are supported in the standards 7 and 7' so that they are freely rotatable, but are restrained 25 against longitudinal movement.

The carriage 13 supports a sound box 14 and control mechanism for shifting the sound box into recording, reproducing or neutral position by actuation of a control lever 65. The sound box 30 and control mechanism therefor are of well known construction and are substantially the same as those described in detail in U. S. Patent to N. H. Holland, No. 1,420,316, entitled Phonographs and issued June 20, 1922. The sound box comprises a 35 frame 32 having a downwardly extending lug 39 to which is pivotally secured a casing 42 having a sound chamber and a diaphragm 41. The frame 32 comprises a neck 33 for attachment of an elbow 34 forming the end of a flexible speaking tube 35. Connection is made between neck 33 and the casing 42 by means of a sliding tube 45. The casing 42 is provided with a tab 42' for coaction with the control mechanism. A stirrup 55 is secured to the diaphragm 41 and carries a recording stylus 56. 40 A floating weight 48 positioned below the casing 42 is likewise pivotally secured to the lug 39. The floating weight 48 is provided with a central hole 41' through which the recording stylus 56 and the stirrup 55 may pass. An advance ball 80, which 45 may be made of sapphire and which has a spherical surface preferably of a radius large in comparison with the radius of the recording and reproducing stylus, is provided on the floating weight for coaction with the record under certain conditions. The floating weight also carries a reproducing stylus arm 58 pivotally secured at 60 and carrying a reproducing stylus 59. The end of the stylus arm 58 opposite to that carrying the stylus, lies at all times within the stirrup 55. The floating weight 48 is also provided with a tab 48' for coaction with the control mechanism.

The control mechanism comprises a pair of lifting dogs 71 and 72 arranged for rotary movement around the guide rod 17. When the control lever 65 is shifted to the forward or recording position (Fig. 3) both of the lifting dogs 71 and 72 are moved in a counterclockwise direction until they are entirely clear of the tabs 48' and 42' with which they respectively coact. Under these conditions the floating weight 48 will move downwardly until the advance ball 80 contacts the record surface and the casing 42 will likewise move downwardly until the recording stylus 56 is also in contact with the record surface. The advance ball 80 contacts the record surface somewhat in

advance of the recording stylus 56 and in consequence, when the mandrel is rotated to cause the recording stylus to cut a phonographic groove in the surface of the record tablet, the advance ball rides on the uncut portion of the record tablet in 5 advance of said stylus. If sound waves impinge upon the diaphragm 41, the depth of the engraving will be varied in accordance therewith and a phonographic record will be made.

When the control arm 65 is shifted to the neutral position both the lifting dogs 71 and 72 are rotated in a clockwise direction and coact with their respective tabs 48' and 42' to lift both the floating weight 48 and casing 42 and also the styli 56 and 59 entirely clear of the record.

When the control arm 65 is moved to its rear or reproducing position, the lifting dog 72 remains in its upper position thus holding the casing 42 against the frame 32 as in the neutral position. The lifting dog 71 however is then again rotated 20 downwardly or in a counterclockwise direction and thereby allows the floating weight to move downwardly away from the casing 42. Under these circumstances the rear end of the reproducer stylus arm 58 is held within the stirrup 55 25 and as a result the reproducing stylus arm 58 is rotated in a counterclockwise direction so that the reproducing stylus 59 will engage the record grooves. When such contact occurs, the advance ball is out of contact with the record surface and the mass of the floating weight serves to bias the reproducer stylus into its record engaging position. As the mandrel is rotated the stylus is 30 vibrated by the record groove and this vibration is transmitted by the arm 58 to the stirrup 55 and consequently to the diaphragm 41, thereby producing sounds corresponding to the engraving on the record. The mechanism whereby the prescribed motions of the lifting dogs 71 and 72 are 35 attained is described in the above mentioned Holland patent and is not therefore described herein. The recording and reproducing mechanism is 40 shown in reproducing position in Fig. 5.

The feeding and back-spacing mechanism, with the exception of the feed screw 20, is mounted on 45 the rear portion of the carriage 13. The construction of the back-spacing and feeding mechanism is identical with that described in my co-pending application Serial No. 375,367, filed July 2, 1929. The carriage 13 at its rear end is in the 50 form of a hollow channel having side walls 90 and 91 and a boss 93. A tube 94 having an internal diameter of the proper size to receive the rear guide rod 18 is fitted into suitable holes in the boss 93 and in the side wall 91 and is secured against 55 movement therein. The tube 94 extends entirely across the space intervening the side walls of the carriage 13 and forms a pivotal mounting for a U-shaped member comprising a rear portion 96 and two side arms 114 and 115. The lower portion of the member 96 is bent inwardly (see Fig. 8) to form a mounting bracket 96'. Mounting bracket 96' is drilled to receive a threaded portion of a shouldered stud 97 which is secured to the bracket by a nut 104. A tubular member 98 comprising a worm gear 99 and having a gear wheel 21 fixed thereto, is rotatably mounted on the stud 97 and is held against longitudinal movement thereon by a screw 101 (see Fig. 9). The gear wheel 21 is arranged for engagement with the 70 feed screw 20 and acts under certain conditions as a feed nut. A leaf spring 117 adjustably secured to the side-wall 91 of the carriage coacts with a pin 116 secured in the side arms 114 and 115 to bias the gear wheel 21 into engagement with the 75

feed screw 20. The worm gear 99 meshes with a worm 100 rotatably mounted on the tube 94. By reason of the frictional resistance in the worm and gear connection, the gear wheel 21 is locked 5 against movement and thereby serves in the same fashion as the more usual form of feed nut when the carriage is being fed across the record by the feed screw. A ratchet wheel 111 is secured concentrically to the worm 100. Adjacent the ratchet wheel 111 a cam 105 is mounted for rotation 10 on the tube 94. A pawl 108 is pivotally mounted on the cam 105 and is biased into engagement with the ratchet wheel 111 by means of a coil spring 110. The cam 105 carries an inwardly extending pin 106 which passes through a short circumferential opening 107 in the tube 94 and into a longitudinal slot 106' in the rear guide rod 18. Adjacent the standard 7' (see Figs. 1 and 2) the back rod 18 is provided with an arm 124 to 15 the outer end of which a connecting lever 123 is rotatably fastened. The opposite end of the connecting lever 123 is secured to an armature 122 designed to coact with a magnet coil 121. When the magnet 121 is energized the armature 122 will 20 be drawn upwardly opposite the core of the magnet which will cause a rotary motion to be imparted to the back rod 18. When such rotary motion occurs, the cam 105 will be rotated because of the engagement of pin 106 in slot 106' and the worm 100 will simultaneously be rotated by reason 25 of the engagement of the pawl 108 with the ratchet wheel 111. Such rotation of the worm 100 will cause the worm gear 99 and the gear wheel 21 to be rotated and a back-spacing motion 30 of limited extent is thereby imparted to the carriage, the feed screw then acting as a rack and the gear wheel 21 as a pinion. When the magnet coil 121 is de-energized, the armature 122 drops down, thus restoring the cam 105 to its original 35 position. The pawl 108 slides back over the ratchet 111, leaving the worm in the position to which it was moved during the back-spacing operation. If a back-spacing motion of greater extent is desired, the magnet coil 121 may be successively energized and de-energized, thus imparting a step by step back-spacing motion to the carriage which may be continued to accomplish 40 any desired extent of backward movement.

The parts of the mechanism thus far described 45 are each separately old in the art. It will be seen that the mechanism provides manual control for the positioning of the recording and reproducing mechanism, as well as means whereby the carriage may be back-spaced. In order to throw the gear wheel 21 out of engagement with the feed screw 20 when the control lever 65 is moved into the neutral position wherein the carriage 13 should be freely movable along the guide rods, a plunger 81 having a rounded head 84 is provided 50 for coaction with a roller 84' (see Fig. 3). When the lever 65 is moved to neutral position the roller 84' pushes the plunger 81 backwardly. A push rod 81' secured to the plunger 81 coacts with the upper end of the rear portion 96 of the U-shaped member which carries the feed wheel 21 and its associated parts. It will be seen that when the plunger 81 moves backwardly under the influence 55 of the roller 84', the portion 96 and consequently the feed wheel 21 will be rotated in a clockwise direction around the rear guide rod 18 and against the tension of the spring 117, thus serving to disengage the gear wheel 21 from the feed nut 20. When the control lever is in either the recording 60 or reproducing position the spring 117 moves the

plunger 81 forward and causes the gear wheel 21 to engage the feed screw 20.

In order to make the operation of this mechanism automatic it is essential that when a back-spacing operation is performed the recorder and reproducer mechanism be simultaneously thrown into reproducing condition. In order to accomplish this an auxiliary lifting dog 136 having a projecting nose 137 is pivotally mounted adjacent the lifting dog 72 in such a way that the projecting nose may also coact with the tab 42' on the casing 42 (see Figs. 3, 4 and 5). The lifting dog 136 is freely rotatable and may be moved independently of the lifting dog 72. A pin 135 is arranged for coaction with a suitable shoulder on 15 the lifting dog 136. The pin 135 is secured to a disk 135' concentric with the lifting dog 136 and is similarly mounted for rotation within a boss 15 on the carriage 13. A coil spring 140 connected between the disk 135' and the outer wall of the 20 boss 15 serves to bias the disk and consequently the pin 135 to a point where the nose 137 of the lifting cam 136 is below and clear of the lifting tab 42'. A connecting rod 131 is pivotally secured to the pin 135 by a suitably drilled U-shaped 25 member 134. The connecting rod 131 passes to the rear of the carriage and is supported in a bearing formed in an L-shaped bracket 141 secured to the inner side of wall 90 of the carriage. The rear end of the connecting rod 131 is arranged for coaction with a top portion 130 of a bail having side arms 128 and 129. The bail is pivoted on one side by a pivot screw 125 passing through the arm 128 and secured in the arm 114, and on the other side by a short shouldered stud 30 126 passing through the arm 129 and secured in the arm 115. A screw 150 threaded in the stud 126 holds the arm 129 in place. A coil spring 133 around the pivot screw 125 biases the bail toward 35 the rear of the carriage. The arm 128 of the bail 40 is provided with a roller 132 for coaction with the nose of the cam 105. It will therefore be seen that when the back-spacing mechanism is operated and the cam 105 rotated, a forward motion will be imparted to the bail which will in turn 45 strike the end of the connecting rod 131 and move the auxiliary lifting dog 136 in a clockwise direction thus lifting the casing 42 upwardly and conditioning the recorder-reproducer mechanism for reproducing (see Fig. 5).

However as soon as the back-spacing mechanism returns to its normal position the recorder-reproducer mechanism would likewise tend to return to the recording position. In order to maintain the mechanism in reproducing position, 55 the connecting rod 131 is provided with a notch 131' for coaction with a latching pawl 142. The pawl 142 is pivoted on the L-shaped bracket 141 by a shoulder screw 143 and is biased into contact with the connecting rod 131 by a coil spring 144. 60 As soon as the connecting rod 131 has been moved forward during a back-spacing movement, the latching pawl 142 falls into the notch 131' and retains the connecting rod 131 in its forward position and thus maintains the sound box in its 65 reproducing position.

The latching pawl 142 has a lower extended portion 145 which in normal operation abuts against a pin 146 carried by a marker plate 147. The marker plate 147 is supported on the back 70 rod 18 adjacent the carriage 13. It is provided with an enlarged collar 148 carrying a pin 151 for engagement with the slot 106' in the back rod 18 whereby it is maintained correctly positioned. It is also provided with a suitable fric- 75

tioning device comprising an adjustable spring 149 and a plunger 149' housed in a well in the collar 148. When the carriage is in the recording position and is moving forward normally the 5 marker plate is pushed along by the side wall 91 of the carriage. By reason of the contact between the pin 146 and the lower end 145 of the latching pawl, the marker plate maintains the upper or latching end of the pawl 142 completely 10 out of contact with the rod 131. However, when a back-spacing motion is imparted to the carriage the marker mechanism is not moved backwardly with the carriage and as a result the latching pawl is then free to fall into the notch 15 131' and thereby to maintain the recording and reproducing mechanism in reproducing condition. When all of the recorded matter has been reproduced, the lower end of the latching pawl 142 will again engage the pin 146 and, upon 20 slightly further advance of the carriage, will withdraw the latching pawl from the notch 131' and allow the connecting rod 131 to move backwardly under the urging of the coil spring 146. The casing 42 will thereupon be released and 25 will drop down until the recording stylus 56 again engages the record and conditions the machine for recording.

In the mechanism just described it will be seen that the recording and reproducing mechanism 30 is returned to recording condition at substantially the same point along the record as that at which the back-spacing motion was started. Such an arrangement might result at times in cutting out a small portion of the groove already recorded or 35 might shift the recording and reproducing mechanism into recording position before the reproduction had been entirely completed. For this reason it is preferable to allow a slight space to intervene before the recording and reproducing mechanism is again conditioned for recording. In order to accomplish this, the stud 126 on which the arm 129 is pivoted is provided with a camming surface 152 on its outward end. A member having a complementary camming surface 153 is secured to the marker plate 147 by 40 a screw 150'. It will therefore be seen that whenever a back-spacing movement is imparted to the carriage, and the marker plate 147 is rotated upwardly by reason of its pin and slot 45 connection with the back rod 18, the marker plate will be cammed to a position slightly in advance of the farthest point of advance of the carriage. Under these conditions when the carriage again moves up to the marker plate and the recording and reproducing mechanism is again conditioned 50 for recording by coaction of the marker plate with the pin 146, there will be a slight gap left between the finish of the previous recording and the start of the succeeding recording.

55 The mechanism above described is available for operation as described as long as the dictation is continued, providing means for repeating and subsequently restoring the mechanism to recording condition whenever desired. However whenever a cylinder is removed from the mandrel and a new cylinder placed thereon it is necessary to move the control lever 65 into the neutral position and to move the entire carriage backwardly toward the starting position. Under 60 these circumstances it is necessary to also retract the marker plate 147 so that it will always be available in connection with the operation of repeating portions of the dictated matter. In order to insure the return of the marker plate 70 75 147 with the carriage, a bracket 160 carrying a

pawl 158 pivoted on a screw 159, is secured to the mounting bracket 96. When the control lever 65 is in recording position the pawl 158 is clear of the marker plate 147 (see Fig. 3) and the relative movement of the carriage and the marker plate is not restricted. However, as soon as the control lever 65 is thrown into neutral position wherein the mounting bracket 96 and the feed screw are rotated about the guide rod 18 in a clockwise direction as seen in Fig. 3, the pawl 158 will be moved inwardly and over the plate 147 as shown in Fig. 3A, so that if the carriage is retracted it will serve to carry the marker plate 147 along. As soon as the control lever is again moved in the recording position the pawl 158 is again moved out of the way of the marker plate. A spring 161 serves to bias pawl 158 to the operative position shown and also permits the pawl to ride over the plate 147 in the event said pawl should be positioned rearwardly thereof by reason of improper operation of the machine and the carriage should then be advanced, with the arm 65 set in neutral, for the purpose of restoring said pawl to its normal position in advance of plate 147. 25

In the construction shown the feed wheel 21 is held against rotation under normal operating conditions by the frictional engagement of the worm wheel 99 with the worm 100. However under some circumstances there may be a certain 30 amount of back-lash or lost motion in the connection of the feed wheel to the carriage and this is very undesirable during the recording operation when it is essential to have the groove engraved upon the record tablet very accurately. 35 For this reason it may be desirable to provide a frictional braking mechanism which will prevent any such lost motion. Such a braking mechanism may comprise a pulley 190 mounted on the sleeve 98 which carries the gear wheel 21. A 40 brake band 190' is secured at one end to a pin 192 fixed in bracket 96' and encircles the brake drum 190. The brake band 190' is secured at its other end to another pin 193 fixed in a plate 194 rotatably mounted on the sleeve 98 adjacent the 45 brake drum 190. The plate 194 has a short extending arm 195 adapted to cooperate with a short arm 196 of a bell crank 197 (see Figs. 4, 7 and 8). Bell crank 197 is pivoted on a pin 198 carried by a bracket 199 secured to the mounting 50 bracket 96'. The long arm of the bell crank is provided with a short finger 202 adapted to bear against the peripheral surface 203 of the cam 105. The shape of the cam is such that when the mechanism is in normal operating condition 55 a considerable tension is maintained on the spring band 190' thus preventing any play or lost motion of the gear wheel 21. However as soon as a back-spacing motion is initiated, the cam 105 moves a slight distance and recedes from finger 202 to release the tension upon the spring band 190' so that the gear wheel 21 is free to roll along the feed screw and thus cause the back-spacing movement described above. 60

The speaking tube comprising the flexible tube 65 35 serves as a sound conduit and is terminated in a mouthpiece 36. The mouthpiece preferably of moulded insulating material, is provided with a clutch controlling switch which comprises a switch box 180 and a cover 183 therefor, the 70 cover being pivoted by a screw and bushing 184. The switch cover is normally biased outwardly and when in this position the clutch is disengaged. Upon pressing the switch cover 183 downwardly the clutch is engaged and the mandrel ro- 75

tated. The construction of the clutch and clutch controlling mechanism is of itself no part of this invention and may be of the type described in Patent No. 1,380,486, to S. G. Langley, dated June 7, 1921, and entitled Controlling device.

In addition to the clutch controlling switch, a second switch is provided within a casing 170 on the speaking tube for controlling the repeating mechanism described herein. This switch comprises a finger-piece 171 of insulating material pivoted in the casing 170 by pins 172. Finger-piece 171 carries a metallic connecting arm 177 adapted, when the finger-piece 171 is rocked in either direction to make contact and establish a circuit between a pair of double-ended contacts 174, 175, thus establishing a circuit through conductors 120, a battery 120' and magnet coil 121, whereby the repeating mechanism on the phonograph is actuated. A coil spring 173 serves to bias the finger-piece 171 to its central or upright position. It is to be noted that the motion required to actuate the repeating control switch is at right angles to that required for the clutch control switch, thus avoiding any confusion as to function. Furthermore closure of the repeating control switch is accomplished by movement of finger-piece 171 in either direction so that successive actuations of the back-spacing mechanism may be quickly effected by rapid oscillation of the finger-piece. It is intended that the finger-piece 171 be moved by the index finger which may be done without moving the hand from its normal position about the clutch control switch.

The operation of the machine is as follows: When it is desired to dictate, a record tablet A is placed on the mandrel, the carriage is moved to the beginning of the tablet and the control lever 65 moved into recording position. The operator then dictates into the mouthpiece, maintaining the switch cover 183 of the clutch control depressed as long as he is speaking into the machine. If during the course of the dictation he should be interrupted and upon returning desire to listen to the last portion of the matter already dictated, or if he should desire to make changes in the matter dictated, or if for any other reason it is necessary that he listen to the previously dictated matter, he rocks or oscillates the finger-piece 171, closing and opening the circuit of the repeat magnet coil 121 one or more times, thus causing any desired number of back-spacing

movements of the carriage as described hereinbefore. During this back-spacing operation, the recording and reproducing mechanism will be conditioned for reproducing and upon completion of the back-spacing motion he may cause the mandrel to rotate by depressing the switch cover 183, whereupon the carriage will again move forward and the matter dictated will be reproduced. When the carriage has traveled a slight distance past the end of the dictated matter, the recording and reproducing mechanism will be automatically restored to the recording condition and he may proceed with his dictation. The extent of the back-spacing motion depends upon the number of oscillations given to the finger-piece 171, one back-spacing operation being performed for each closure of the switch 171, 174, 175. It is to be understood that if more than one back-spacing operation is performed, the operations subsequent to the first one will merely result in further retraction of the carriage, the other necessary functions having been performed with the first back-spacing operation.

Having thus described my invention, I claim:

1. In a phonograph, a carriage, a feed screw, 25 carriage advancing means comprising a rotatable feed nut mounted on said carriage for coaction with said feed screw, means to lock said feed nut against play relatively to said carriage during an advancing movement, back-spacing mechanism for said carriage, said mechanism being adapted to cause rotation of said feed nut to effect backspacing movement, and means associated with said mechanism to render said locking means inoperative during a back-spacing operation.

2. In a phonograph, a sound box, a feed screw, sound box advancing means comprising a gear wheel mounted for coaction with said feed screw, braking means to eliminate play in said feed 40 wheel when it acts as a feed nut during advancing movement of the sound box, sound box back-spacing mechanism comprising means to rotate said gear wheel whereupon it coacts with said feed screw as a pinion on a rack to effect back-spacing, and means associated with said back-spacing mechanism for rendering said braking means inoperative during operation of said back-spacing mechanism.

HEINRICH F. MAX GRAMANN.
